UNITED STATES PATENT OFFICE.

CHARLES A. UFFORD, OF DORCHESTER, MASSACHUSETTS.

DRESS FORM.

Application filed May 5, 1921. Serial No. 466,869.

To all whom it may concern:

Be it known that I, CHARLES A. UFFORD, a citizen of the United States, and resident of Dorchester, county of Suffolk, State of Massachusetts, have invented an Improvement in Dress Forms, of which the following description, in connection with the accompanying drawing, is a specification, like characters on the drawing representing like parts.

This invention relates to sectional dress forms, and it has for one of its objects to provide a novel sectional dress form which is constructed so as to provide a solid section underneath each arm instead of the usual space or division between the front and back portions of the form. This construction has the advantage that it is much easier to fit a waist or waist lining thereto because of the solid support which is afforded under each arm.

Another object of my invention is to provide a novel sectional dress form in which the number of clamping bolts which are necessary for clamping the sections in adjusted position is reduced, thus making it easier to adjust the form. Still another object of the invention is to provide a novel and simplified connection between the hip sections and the center supporting tube.

Other objects of the invention are to improve dress forms of this type, all as will be more fully hereinafter set forth.

In order to give an understanding of my invention, I have illustrated in the drawings a selected embodiment thereof which will now be described, after which the novel features will be pointed out in the appended claims.

In the drawings:

Fig. 1 is a vertical, sectional view through a dress form embodying my invention;

Fig. 2 is a vertical section taken at right angles to Fig. 1 showing the back of the dress form;

Fig. 3 is a section on the line 3—3 of Fig. 2.

Fig. 4 is a view similar to Fig. 2 showing the front of the form.

My improved dress form is of that type which comprises a plurality of sections adjustable relative to each other. It is divided horizontally at the waist as shown at 1, and the front thereof is also divided horizontally above the bust, as shown at 2. The back is divided horizontally just below

the shoulders, as shown at 3. The form is also divided vertically, and the vertical divisions with the horizontal divisions make up the sections of the form. The form is divided vertically from front to rear at each side of the center and through each shoulder, as shown by the division lines 4. The neck portion is divided into four sections, and the four neck sections, two on the front, two on the rear, extend from the neck down to the horizontal division lines 2 and 3. The front neck sections are indicated at 5 and the rear neck sections at 6. The form is also divided vertically at each side along the two division lines 7 and 8, which are situated either side of the arm hole 9, these divisions 7 and 8 preferably extending from the arm hole to the bottom of the form. This manner of dividing the form produces a solid bust section 39 at the front of the form from the horizontal division line 2 to the waist line, and a similar solid back section 10 at the back of the form. It also produces two under-arm sections 11 at the sides of the form beneath the arm holes, the two side bust sections 40, the two side back sections 26, and the eight hip sections 13. The dress form, therefore, has the solid sections 11 under each arm hole at the sides of the form, and also the sections 39 and 10 at the front and rear. This is of advantage in fitting a waist because it gives solid support to the garment directly at the front and rear and underneath each arm. The eight hip sections 13 are all adjustably secured to a four-armed member 14 which is secured to the central standard or support 15 in usual manner. This support 14 has the four slotted arms 16. The front and rear sections 13 have horizontally extending plates 17 secured thereto, which are adjustably clamped to two of the slotted arms 16 by means of clamping bolts 18. The other six hip sections 13 also have horizontally extending plates 19 secured thereto and the three plates 19 extending from the three sections on each side of the form have an overlapping relation and are secured to the other arms of the fore-armed member. These three overlapping plates 19 at each side of the form are so arranged that the central plate is interposed between the two outside plates. The outside plates each have inclined slots 20 therein, the slot 20 of one outside plate of each group having a crossing relation with the slot 20 of the

other outside plate. The central plate of each group of three has an aperture therein. A clamping bolt 21 extends through the crossing slots and through the aperture which is in alignment therewith and by means of this arrangement a single clamping bolt is sufficient for clamping in position the three of the hip sections at each side of the form. Owing to the crossing relation of the slots the three hip sections of any form can be all expanded radially whenever this corresponding bolt 21 is loosened.

The dress form is also provided with hinged waist sections 12 at the front and sides thereof, which sections are hinged to the hip sections by hinges 22. The bust sections and under-arm sections are adjustably secured to the hinged waist sections 12 by means of slotted clamping members 23, which are fixedly anchored at their upper ends to the bust and under-arm sections, and which overlie the hinged waist sections. These members 23 are adjustably secured to the waist sections by clamping bolts 24 which extend through the slots in said members and are anchored in the hinged waist sections. This construction permits the form to be lengthened vertically.

In order to hold the waist sections properly adjusted relative to each other to give any desired waist-line measurement, I have provided horizontal slotted members 25 which are secured to certain of the hinged waist sections and overlie other hinged waist sections and are adjustably secured thereto by the clamping bolts 24. These members 25 act as tie members, and they serve not only to hold the hinged waist sections properly placed relative to each other, but they also serve to hold the lower ends of the bust and under-arm sections properly placed. It is not, therefore, necessary to have any tie members directly connecting the lower ends of the bust and under-arm sections, and thereby I am enabled to reduce materially the number of slotted members and clamping bolts which are necessary to hold the dress form in any adjusted position. The back section 10 is connected to each of the back shoulder sections 27 by means of a slotted clamping member 28, and each of the sections 26, which are situated either side of the section 10, are connected to the section 27 by a similar clamping member 29. The clamping members 28 and 29 for each section 27 are adjustably secured thereto by a single clamping bolt 30. Each neck section 6 is also secured to the adjacent shoulder section 27 by means of a slotted member

31, which also cooperates with the bolt 30. Each bolt 30, therefore, serves as a means for controlling the adjustment of the four sections 6, 27, 26 and 10 relative to each other.

A similar construction is used on each side of the form for securing together the central bust section 39, the side bust section 40, the front shoulder section 42, and the front neck section 5 when they corner together as seen in Fig. 4.

I claim:

1. A dress form divided vertically from front to rear through each shoulder, and having two vertical divisions extending from each armhole, thereby to provide a solid under arm section at each side of the form, and means for adjustably connecting such sections together.

2. A dress form divided horizontally at the waist, and horizontally above the bust line, and also divided vertically from front to rear through each shoulder, and divided from side to side from the neck portion to the armhole, and divided vertically from front to rear from the neck to the upper horizontal division, said form also having two vertical divisions at each side extending from the armhole to the bottom of the form, whereby solid under-arm sections are provided, and a solid section is also provided centrally at the front and rear below the upper horizontal division.

3. A dress form divided vertically in eight places to form eight vertical sections, two vertical divisions on each side of the form extending from the corresponding armhole thereby to provide a solid under arm section at each side of the form, in combination with a standard, a four-armed member secured thereto, each arm of said member being radially slotted, and anchoring plates secured to each of the vertical sections, the plates of the front and rear sections being adjustably secured to two opposite arms of the four-armed member, and the plates of the three sections on each side of the form overlapping each other and being secured to the other arms of said four-armed member, the outside plates of each group of three being slotted with the slots crossing each other and the central plate of each group having an aperture in alignment with the point where the slots cross, and a clamping bolt extending through the aligned aperture and slots and through the slot of the corresponding arm.

In testimony whereof, I have signed my name to this specification.

CHARLES A. UFFORD.
